(No Model.)

W. P. MILLER.

STAND FOR DISPLAYING BOXES, &c.

No. 462,084.

Patented Oct. 27, 1891.

THE NORRIS PETERS CO., PHOTO-LITHO., WASHINGTON, D. C.

UNITED STATES PATENT OFFICE.

WILLIAM P. MILLER, OF PHILADELPHIA, PENNSYLVANIA, ASSIGNOR TO
THOMAS DE Q. RICHARDSON, OF SAME PLACE.

STAND FOR DISPLAYING BOXES, &c.

SPECIFICATION forming part of Letters Patent No. 462,084, dated October 27, 1891.

Application filed April 2, 1891. Serial No. 387,384. (No model.)

To all whom it may concern:

Be it known that I, WILLIAM PRINGLE MILLER, a citizen of the United States, residing in the city and county of Philadelphia, State of Pennsylvania, have invented a new and useful Improvement in Stands for Displaying Boxes, &c., which improvement is fully set forth in the following specification and accompanying drawings.

10 My invention consists of a stair-shaped stand having novel features, as hereinafter pointed out.

It also consists of a stair-shaped stand having guards for preventing boxes, &c., placed thereon from slipping therefrom.

15 It also consists in providing the stand with a base and prop, which are hinged to the stand so as to be folded therewith.

It further consists of novel means for locking the base and prop.

It also consists in providing the stand with a leg, which provides means for securing the same to a counter, table, &c., and preventing shifting thereof.

20 Figure 1 represents a perspective view of a stand embodying my invention. Fig. 2 represents a vertical section thereof. Fig. 3 represents a perspective view of the stand in folded condition. Figs. 4 and 5 represent perspective views of detached portions on an enlarged scale. Fig. 6 represents a perspective view of a portion of another form of the stand. Fig. 7 represents a vertical section on line xx , Fig. 6.

25 Similar letters of reference indicate corresponding parts in the several figures.

Referring to the drawings, A designates a stand formed of the stair-shaped body B, a base C, and prop D, said base and prop being 30 hinged to said body, so as to be capable of being folded thereagainst, as will be seen in Fig. 3, for purposes of packing, storing, transportation, &c. The forward part E of each step of the stair-shaped body rises above the 35 sides thereof, thus forming guards, whereby when boxes, &c., are supported on the steps they are prevented from slipping forward, owing to the said guards. In the lower part of the prop is a recess F, which is occupied 40 by a tongue G, hinged to said prop, and the lower wall of said recess has a dovetailed groove H to receive a dovetailed tongue J on the rear end of the base C, it being seen that when the tongue J is in the groove H and

the tongue G inserted into the recess F, said tongue G fills the portion of the recess above the tongue J and closes against the latter, thus preventing rising of the base. As the base is furthermore locked to the prop by the dovetailed tongue and groove J H, the disconnection of the base and prop is prevented, and thus closing or folding of the stand is prevented. When the tongue G is thrown out the base may be raised, thus releasing the dovetailed tongue J and permitting the separation of the base and prop and the folding of the same. Depending from the rear of the stand is a leg K, which extends below the base C, and is in the present case a downward prolongation of the prop and abuts 70 against the edge of the top of a counter, table, &c., and may be screwed or otherwise secured thereto, thus preventing displacement or overturning of the stand.

In Figs. 6 and 7 the sides of the body are 75 beveled so as to permit circular or round boxes to be set thereinto, as shown by the dotted lines, Fig. 7. The sides of the body are separated, forming a space through which dirt or dust may drop, and which permits 80 boxes to be seated deeply into the steps when so desired.

Having thus described my invention, what I claim as new, and desire to secure by Letters Patent, is—

85 1. A stand having a body, base, and prop, said base having a locking-tongue and said prop having a recess with a groove to receive said tongue and carrying a hinged tongue adapted to fit over and lock the tongue of the 90 base in the said recess of the prop, said parts being combined substantially as described.

2. A stand having a base and prop hinged to the body thereof and connected by a locking tongue and groove, and furthermore secured by a removable tongue on the prop, the same engaging with the tongue on the base, substantially as described.

3. In a stand, the prop D, having a recess F, and a tongue G, adapted to enter the same, 100 in combination with the base C, having a tongue adapted to interlock with said prop and be controlled by said tongue G, substantially as described.

WILLIAM P. MILLER.
